(57) **CLAIM**

The ornamental design for stand up paddleboard, as shown and described.

DESCRIPTION

FIG. 1 is a front view of a stand up paddleboard.

FIG. 2 is a back view of the stand up paddleboard shown in FIG. 1.

FIG. 3 is a top view of the stand up paddleboard shown in FIG. 1.

FIG. 4 is a bottom view of the stand up paddleboard shown in FIG. 1.

FIG. 5 is a left view of the stand up paddleboard shown in FIG. 1.

FIG. 6 is a right view of the stand up paddleboard shown in FIG. 1.

FIG. 7 is a perspective view of the stand up paddleboard shown in FIG. 1.

FIG. 8 is a front view of a part of a stand up paddleboard.

FIG. 9 is a back view of the part of the stand up paddleboard shown in FIG. 8.

FIG. 10 is a top view of the part of the stand up paddleboard shown in FIG. 8.

FIG. 11 is a bottom view of the part of the stand up paddleboard shown in FIG. 8.

FIG. 12 is a left view of the part of the stand up paddleboard shown in FIG. 8.

FIG. 13 is a right view of the part of the stand up paddleboard shown in FIG. 8.

FIG. 14 is a perspective view of the part of the stand up paddleboard shown in FIG. 8.

FIG. 15 is a front view of an inner stand up paddleboard.

FIG. 16 is a back view of the inner stand up paddleboard shown in FIG. 15.

FIG. 17 is a top view of the inner stand up paddleboard shown in FIG. 15.

FIG. 18 is a bottom view of the inner stand up paddleboard shown in FIG. 15.

(Continued)

FIG. 19 is a left view of the inner stand up paddleboard shown in FIG. 15.

FIG. 20 is a right view of the inner stand up paddleboard shown in FIG. 15; and,

FIG. 21 is a perspective view of the inner stand up paddleboard shown in FIG. 15.

The broken line showing of the stand up paddleboard is for the purpose of illustrating portions of the article that forms no part of the claimed design.

1 Claim, 7 Drawing Sheets
